CONTROL SWITCH

Filed Nov. 4, 1940

UNITED STATES PATENT OFFICE

2,273,381

CONTROL SWITCH

Burton E. Shaw, Bristol, Ind., assignor to Penn Electric Switch Co., Goshen, Ind., a corporation of Iowa

Application November 4, 1940, Serial No. 364,269

16 Claims. (Cl. 200—139)

My present invention relates to a control switch, particularly one of the kind adapted to respond to temperature of a surface to which the switch is attached.

One object of the invention is to provide a compact switch structure adapted to control voltages of 110 or 220, with the parts of the switch comparatively simple and inexpensive to manufacture and install.

Another object is to provide a "surface" switch having a temperature responsive element that is isolated from the body of the switch by an insulating base member and enclosed within a metallic housing having parts in contact with a steam or hot water pipe to facilitate transmission of heat from the pipe surface to the temperature responsive element of the switch, the switch being thereby quickly and accurately responsive to such heat.

Another object is to provide a switch structure wherein compactness is secured by designing a base member having a central hub for an adjusting shaft of a coiled bimetallic element with a conduit connection mounted on one side of the hub and the switch mechanism mounted on the other side, terminals for the wires of the conduit being mounted on opposite sides of the hub and between the switch and conduit fitting.

Still a further object is to provide a bracket for the conduit fitting which serves also as a stop for an adjusting knob and as a means to which the cover is secured.

A further object is to provide a switch structure which may be mounted in any position, yet has a dial which is readily readable for setting the range of operation.

With these and other objects in view, my invention consists in the construction, arrangement and combination of the various parts of my device whereby the objects contemplated are attained, as hereinafter more fully set forth, pointed out in my claims and illustrated in the accompanying drawing. Although the invention is susceptible of a variety of embodiments, it is unnecessary to fully describe and illustrate more than one in order to give a full understanding of the invention both from its structural and functional standpoints. Accordingly, I have illustrated a preferred and desirable embodiment of the invention in the accompanying drawing, in which:

Figure 1 is a perspective view of my control switch showing it mounted on a steam pipe or the like;

Figure 2 is a horizontal sectional view as taken on the line 2—2 of Figure 1;

Figures 3, 4 and 5 are vertical sectional views taken on the lines 3—3, 4—4 and 5—5, respectively, of Figure 2; and

Figure 6 is a bottom plan view of the control switch with a portion of one of the plates broken away to show constructional features.

On the accompanying drawing, I have used the reference character B to indicate in general a base member and C a cover therefor. The members B and C are preferably of insulating material. The base member B has a recess 10 in its bottom surface into which a depressed part 12 of a first base plate 13 extends. A second base plate 14 is provided with extensions 15 which are shaped to fit the surface of a pipe 16. The extensions 15 are secured to the pipe 16 and held tightly in thermal contact therewith by a pair of clamp bands 17.

The base member B has a central hub 18 through which an adjusting shaft 19 rotatably extends. The shaft 19 has a head 20 within a temperature responsive element housing formed by the base plate 14 and the upwardly depressed portion 12 of the base plate 13. The head 20 is slotted as at 21 to receive one end of a coiled bimetal element 22. The lower end of the head 20 frictionally engages the base plate 14 under the bias of a spring friction washer 23 located between the head 20 and the portion 12 of the base plate 13. The lower end of the adjusting shaft 19 is journaled in a perforation 24 of the base plate 14.

Spaced from the hub 18 on one side of the shaft 19 is an upward projection 25 from the base member B. A bracket 26 extends upwardly from the other side of the base member, the bracket being secured to the base member by screws 27 passing through ears 28 of the bracket and threaded into the base member. The bracket 26 is bent L-shaped and is provided with an opening 29 to rotatably receive the adjusting shaft 19. Beyond the adjusting shaft the bracket 26 has an upwardly extending stop lug 30. An adjusting knob 31 is mounted on the shaft 19 as by a set screw 32 and has an arcuate groove 33 receiving the stop lug 30. The groove 33, as shown by dotted lines in Figure 2, limits the rotation of the adjusting knob 31 to substantially 180°.

The cover C is mounted on the base B and retained in position thereon by a pair of screws 34 and 35 extending into the bracket 26 and the projection 25, respectively. The cover is pro-

vided with a pair of beads 36 on its inner wall to enter slots 37 formed in extensions 18^a of the hub 18.

Between the hub 18 and the projection 25, I mount a switch structure including a switch arm 38 having a pair of ears 39 pivoted on a pivot pin 40. The pivot pin 40 is carried by the hub 18 and the projection 25, as shown in Figure 3. The switch arm 38 is of magnetic material and a permanent horseshoe magnet 41 is provided to impart snap action thereto. The magnet 41 is retained in a socket 42 of the base member B by a screw 43. The switch arm 38 carries a substantially straight leaf spring 44 having thereon a movable contact 45. The leaf spring is anchored at one end to the switch arm by a screw 46 and at its other end extends through a slot 47 which permits limited lost motion of the leaf spring relative to the switch arm.

A stationary contact 48 is carried by a differential adjusting screw 49 which in turn is threaded through a supporting plate 50. The supporting plate 50 has one end mounted on one of the hub extensions 18^a by a terminal screw 51 and its other end mounted on a lateral extension 25^a of the projection 25 as by a rivet or the like 52. An adjusting knob 53 is mounted on the screw 49 and cooperates with a dial 54 formed on the mounting plate 50.

A second terminal screw 55 is mounted on the other extension 18^a and it is connected by a pigtail 56 to a bracket 57 secured in position on the switch arm 38 by the screw 46. The bracket 26 is adapted to support a conduit fitting 58 into which a conduit 59 extends. The electric wires 60 in the conduit connect with the respective terminals 51 and 55.

To provide an operative connection between the coiled bimetal 22 and the switch arm 38, I provide an actuating arm 61 formed preferably of insulating material and secured as by a screw 62 to the switch arm 38 as shown in Figure 5. The lower end of the actuating arm 61 has a seat 63 for a thrust blade 64 on the free end of the bimetal element 22 to give a knife edge bearing at this point. To retain the bearing elements in contact, a finger 65 extends from the blade 64 and partially encircles the actuating arm 61. To accommodate the actuating arm 61 and the necessary movement thereof, the base member B is provided with an opening 61^a and the base plate 13 is provided with an opening 61^b.

Cooperating with the adjusting knob 31, I provide a dial plate 66 having a pair of indicating scales 67 and 68 thereon. The knob 31 has a pair of pointers 69 and 70 cooperating with the respective scales 67 and 68. The scales are arranged double in the manner illustrated in Figure 1 so that the control switch can be mounted with the conduit 59 extending either to the right or to the left. In one of these positions, one of the scales is readily readable in conjunction with the adjusting knob, while in the other position the other scale would be used.

The base plates 13 and 14 are secured in position as by countersunk screws 71 as shown in Figure 6. The screws 71 extend through keyhole type openings 72 in the base plate 14 and through enlarged openings 73 in the base plate 13. The keyhole openings are arranged so that the screws can be loosened and the base plate 14 rotated slightly and then removed for access to the bimetal element 21.

Practical operation

My control switch is particularly adapted to be installed in series with an oil burner motor so as to act as a limit switch for a steam or hot water heating system. Obviously, it is adaptable for use wherever temperature response is desired, with the temperature taken from the surface of a pipe or the like. Normally the switch is closed as shown in Figure 5. The knob 31 is adjusted for the desired temperature range so that when the temperature setting is reached the switch will cut out. A rise in temperature causes the bimetal coil 22 to contract, thereby swinging the actuating lever 61 of Figure 5 in a left hand direction. Due to the attraction of the magnet 41 for the switch arm 38, tension will be built up in the bimetal element 22 until such tension overcomes the pull of the magnet, whereupon the actuating arm 61 will quickly swing toward the left, thus lowering the right hand end of the switch arm 38 in Figure 5. Such movement will first bring the upper edge of the lost motion opening 47 into contact with the top of the leaf spring 44 and then the leaf spring will move with the switch arm and separate the contact 45 from the contact 48.

As the temperature in the pipe 16 recedes, it will eventually expand the coiled bimetal element 22 until it swings the switch arm 38 to a position where the magnet 41 will snap it to closed position. The differential of operation or number of degrees difference between cut-out and cut-in of the switch may be adjusted by the adjusting screw 49 which predetermines the distance of the switch arm 38 from the magnet 41 in the closed circuit position of the switch. The smaller such distance, the greater will be the differential of operation.

The arrangement of parts is such that a very compact switch is the result. The switch, though designed for heavy currents, is quite small, as shown on the drawing wherein Figures 2 to 6 are drawn full size. The arrangement of the switch mechanism on one side of the hub 18 and the conduit fitting 58 on the other side, with the switch terminals 51 and 55 on opposite sides of the adjusting shaft 19 and the shaft being centrally located, all contribute to compactness of design.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. In a control switch, a base member of insulating material having a recessed portion in its lower surface, a pair of base plates secured to the bottom of said member, one of said base plates having a depressed portion entering said recess to form a temperature responsive element housing in conjunction with the other base plate, a range adjusting shaft extending centrally downward through said base member and into such housing, a temperature responsive element mounted on said shaft within such housing, means for securing said other base plate to the surface of a pipe or the like to receive heat therefrom by conduction and to transfer such heat by conduction through said plates and by conduction and radiation to said temperature responsive element.

sive element, a switch on said base member having an actuating element extending into such housing, an operative connection between said temperature responsive element and said actuating element, a cover of insulating material for said switch, said cover being mounted on said base member, said cover having an indicating dial thereon and a knob on said adjusting shaft cooperating with said indicating dial.

2. In a control switch, a base member, a pair of base plates secured to the bottom thereof to form a temperature responsive element housing in conjunction with each other, a range adjusting shaft extending centrally downward through said base member and into such housing, a coiled bimetal element mounted on said shaft within such housing, means for securing one of said base plates to the surface of a pipe or the like to receive heat therefrom by conduction, and to transfer such heat by conduction through said plates and by conduction and radiation to said bimetal element, a switch on said base member having an actuating element extending into such housing, an operative connection between said bimetal element and said actuating element, a bracket secured to said base member, a conduit fitting connected therewith, said bracket having a perforation through which said adjusting shaft extends, said bracket beyond said shaft having an upturned stop portion, a knob on said shaft having an arcuate groove to receive said stop portion, said base member having a hub for said shaft and a projection spaced from said hub, said switch including a switch arm between said hub and said projection, a pivot pin for said switch arm having its ends mounted in said hub and said projection, a cover on said base member for said switch, and mounting screws for said cover projecting into said bracket and projection.

3. In a control switch, a base member, a pair of base plates secured to the bottom thereof, one of said base plates being relatively flat, the other of said base plates having a humped center providing a space between the plates to form a temperature responsive element housing said base member having a recess in its bottom surface to receive said humped center of said other base plate, a range adjusting shaft extending centrally downward through said base member and into such housing, a coiled bimetal element mounted on said shaft within such housing, means for securing said first base plate to the surface of a pipe or the like to receive heat therefrom, a switch on said base member having an actuating element extending into such housing, an operative connection between said bimetal element and said actuating element, and a cover for said switch.

4. In a control switch of the character disclosed, a base member having a central bore, a range adjusting shaft rotatable in said bore, a flat base plate and a base plate having an upwardly depressed part secured to the bottom of said base member and forming a temperature responsive element housing, said bottom of said base member having a recess therein to receive said part, said range adjusting shaft extending into such housing, a coiled bimetal element mounted on said shaft within said housing, a switch on said base member having an actuating element extending into such housing, an operative connection between said bimetal element and said actuating element, a cover for said switch mounted on said base member, said cover having an in-

dicating dial thereon and a knob on said range adjusting shaft cooperating with said indicating dial.

5. In a control switch, a base member having a recessed portion in its lower surface, a pair of base plates, one of said base plates having a depressed portion entering said recess to form a temperature responsive element housing in conjunction with the other base plate, a range adjusting shaft extending downwardly through said base member and into such housing, a coiled bimetal element mounted on said shaft within such housing, means for securing such housing to the surface of a pipe or the like to receive heat therefrom, a switch on said base member having an actuating element extending into such housing, an operative connection between said bimetal element and said actuating element, and a knob on said adjusting shaft.

6. In a control switch, a base member, a range adjusting shaft extending through said base member, a coiled bimetal element mounted on said shaft, a switch on said base member having an actuating element, an operative connection between said bimetal element and said actuating element, a bracket secured to said base member and having a perforation through which said adjusting shaft extends, said bracket having an upturned stop portion, a knob on said shaft having an arcuate groove to receive said stop portion, a cover on said base member for said switch, and a mounting screw for said cover projecting into said bracket.

7. In a control switch, a base member, a range adjusting shaft extending through said base member, a coiled bimetal element mounted on said shaft, a switch on said base member having an actuating element, an operative connection between said bimetal element and said actuating element, a bracket secured to said base member, a conduit fitting connected therewith, said bracket having a perforation in which said adjusting shaft is journaled, a knob on said shaft, said base member having a projection spaced from said shaft, a cover on said base member for said switch, and mounting screws for said cover projecting into said bracket and projection.

8. In a control switch, a base member, a pair of base plates secured to the bottom thereof to form, in conjunction with each other, a temperature responsive element housing, a range adjusting shaft, a coiled bimetal element mounted on said shaft within said housing, means for securing one of said base plates to the surface of a pipe or the like to receive heat therefrom, a switch on said base member having an actuating element extending into such housing, an operative connection between said bimetal element and said actuating element, said base member having a central bore for said adjusting shaft, said switch being mounted on one side of said shaft, a conduit fitting mounted on the other side of said shaft, terminals for said switch mounted on opposite sides of said shaft between said switch and said conduit fitting, said conduit fitting being adapted to connect with a conduit carrying wires for connection with said terminals, a cover for said base member and switch, a knob on said adjusting shaft, said cover having a dial for said knob, said dial having a pair of scales for cooperation with a pointer on said knob whereby said base member may be installed in any desired position and thereafter readily read and adjusted.

9. A control switch comprising a base member, a metallic temperature responsive element housing thereon, a range adjusting shaft extending through said base member and into such housing, a coiled bimetal element mounted on said shaft within said housing, means for securing said housing to the surface of a pipe or the like to receive heat therefrom by conduction, a switch on said base plate having an actuating element extending into such housing, an operative connection between said bimetal element and said actuating element, a bracket secured to said base member, said bracket having a perforation through which said adjusting shaft extends, said base member having a hub for said shaft and a projection spaced from said hub, said switch including a switch arm, a pivot pin for said switch arm having its ends mounted in said hub and said projection, a cover on said base member for said switch, and mounting screws for said cover projecting into said bracket and projection.

10. In a control switch, a base member, a range adjusting shaft extending through said base member, a coiled bimetal element mounted on said shaft, a switch on said base member having an actuating element, an operative connection between said bimetal element and said actuating element, said base member having a hub for said adjusting shaft, a conduit fitting on one side of said hub, said switch being mounted on the other side of said hub, terminals for said switch mounted on opposite sides of said hub between said switch and said conduit fitting, said conduit fitting being adapted to connect with a conduit carrying wires for connection with said terminals, a cover for said base member and switch, and a knob on said adjusting shaft, said cover having a dial for said knob.

11. A control switch comprising a base member, a pair of base plates secured to the bottom thereof to form a temperature responsive element housing, a range adjusting shaft extending through said base member and into such housing, a spiral bimetal element having its inner end connected to said shaft and located within such housing, a switch on said base member having an actuating element extending into such housing, an operative connection therein between the outer end of said bimetal element and said actuating element, said switch being mounted on one side of said shaft, a conduit fitting mounted on the other side thereof and being adapted to connect with a conduit carrying wires for connection with said switch, and a knob on said adjusting shaft.

12. In a control switch, a base member, a pair of base plates secured to the bottom thereof to form a temperature responsive element housing, a range adjusting shaft extending centrally downward through said base member and into such housing, a coiled bimetal element mounted on said shaft within said housing, a switch on said base member having an actuating element extending into such housing, an operative connection between said bimetal element and said actuating element, a bracket secured to said base member, a conduit fitting connected therewith, said bracket having a perforation through which said adjusting shaft extends, said bracket beyond said shaft having an upturned stop portion, a knob on said shaft having an arcuate groove to receive said stop portion, said base member having a hub for said shaft and a projection spaced from said hub, said switch in-

cluding a switch arm between said hub and said projection, a magnet to impart snap action to said switch arm, a pivot pin for said switch arm having its ends mounted in said hub and said projection, a cover on said base member for said switch, mounting screws for said cover projecting into said bracket and projection, said switch arm having a contact carried thereby, a mounting plate having another contact supported thereby, said mounting plate spanning said hub and projection and having said other contact adjustable relative thereto to change the differential of operation of said switch by varying the distance of the switch arm relative to the magnet in closed circuit position of the switch.

13. A control switch comprising a base member, a range adjusting shaft through said base member, a bimetal element mounted on said shaft, a switch on said base plate having an actuating element operatively connected with said bimetal element, a knob on said shaft, said base member having a hub for said shaft and a projection spaced from said hub, said switch including a switch arm between said hub and said projection, a pivot pin for said switch arm having its ends mounted in said hub and said projection, said switch arm having a contact carried thereby, and a mounting plate having a contact supported thereby, said mounting plate spanning said hub and projection.

14. In a control switch, a base member, a range adjusting shaft extending through said base member, a bimetal element mounted on said shaft, a switch on said base plate having an actuating element operatively connected with said bimetal element, said switch including an arm and a leaf spring having limited lost motion relative to said arm, a contact carried by said leaf spring, and a stationary contact for cooperation therewith.

15. In a control switch, a base member, a range adjusting shaft extending through said base member, a bimetal element mounted on said shaft, a switch arm on said base plate having an actuating element operatively connected with said bimetal element, said switch arm having a leaf spring provided with limited lost motion relative said arm, a movable contact carried by said leaf spring, and a stationary contact for cooperation therewith, said stationary contact being adjustable to stop said movable contact and switch arm in a predetermined position to vary the differential of operation of the switch.

16. In a control switch, a base member, a pair of base plates secured to the bottom thereof to form a temperature responsive element housing, a range adjusting shaft extending through said base member and into such housing, a bimetal element mounted on said shaft within said housing, means for securing one of said base plates to the surface of a pipe or the like to receive heat therefrom, a switch on said base plate having an actuating element extending into such housing, an operative connection between said bimetal element and said actuating element, said switch including a switch arm, a magnet for imparting snap action thereto, a movable contact carried by said switch arm, and a stationary contact for cooperation therewith, said stationary contact being adjustable to stop said movable contact and switch arm in a predetermined position relative to said magnet to vary the differential of operation of the switch.

BURTON E. SHAW.
